W. C. McLAUGHLIN

AMALGAMATOR

Filed Feb. 15, 1922

Inventor
WILLIAM CORDICE McLAUGHLIN

By *Harry G. Schneider*
Attorney

UNITED STATES PATENT OFFICE.

WILLIAM CORDICE McLAUGHLIN, OF OAKLAND, CALIFORNIA

AMALGAMATOR.

Application filed February 15, 1922. Serial No. 536,674.

To all whom it may concern:

Be it known that I, WILLIAM CORDICE McLAUGHLIN, a citizen of the United States, residing at Oakland, in the county of Alameda and State of California, have invented certain new and useful Improvements in Amalgamators, of which the following is a specification.

My invention is an improved gold separator, particularly useful for separating flour gold, which is constructed so that it may be readily taken apart to amalgamate the interior and for repairs. The amalgamated gold falls through the separator and lodges in a sump at the bottom.

Referring to the annexed drawing in which my invention is illustrated and which forms a part of this specification:

Figure 1 is a transverse sectional view of my amalgamator.

Figure 2 is a fragmentary side view of the same.

My gold separator includes a plurality of superimposed drums 1, 2, 3 and 4, a chute 5 leading at an angle into the uppermost drum 4, a sump 7 below the lowermost drum 1 with which said drum communicates.

In my amalgamator, the rear halves of the drums 1, 2 and 3, the entire chute 5 and the entire sump 7 are formed in one casting 100, while the forward portion of said drums and said sump are formed in one casting 101. Angle irons 102 are secured to each side of the casting 100 at the forward edges thereof, with one member of said bars outstanding from said forward edges of said casting. Angle irons 103 are secured to each side of the casting 101 at the rear edges thereof with one member of said bars outstanding from said rear edges of said casting and resting against the outstanding flanges of the angle bars 102. The outstanding members of the angle bars 103 are provided with a series of vertical slots 104. The bolts 53 extend through the slots 104 and screw into the outstanding flanges of the angle irons 102 to hold the castings 100 and 101 in proper relative position. By means of the slots 104 the casting 101 may be adjusted vertically with relation to the casting 100 to vary the size of the ports 35, 36, 37 between the drums 3 and 4, 2 and 3 and 1 and 2 and the size of the port 38 between the drum 1 and sump 7 respectively. A coarse vertical screen 105 is secured across the front of the casting 100

at its lower end to the sump 7 and at its upper edge to the front wall of the chute 5, said screen extending through the ports 35, 36, 37 and 38 and dividing the drums 1, 2 and 3, the sump 7 and the drum 4 and chute 5. A plurality of semi-circular screens 106 of different diameters and finer mesh than screen 105 are secured to the screen 105 concentrically within the rear half of drum 1, the forward half of drum 2, the rear half of drum 3 and the forward half of drum 4 respectively.

The screens 105, 106, 107 and 108 are copper and are coated with mercury. The flour gold in passing through these screens unites with the mercury and drops into the sump because of its increased weight. The gold passes through the screens with the water and is caused to wash from side to side and comes into contact with a large amalgamated surface in this way so that there is very little possibility of losing any of the gold.

A liquid emulsion of sand and flour gold is placed in the chute 5 and passes from the chute through screen 105, into drum 4 through screens 106, 107 and 108 in said drum, then through port 35 into drum 3 through screens 105 and screens 106, 107 and 108 in said drum, then through port 36 into drum 2 through screen 105 and through screens 106, 107 and 108 in said drum, then through port 37 into drum 1 through screen 105 and through screens 106, 107 and 108 in said drum and then through port 38 into sump 7 and out, the gold being caught in the screens 106, 107 and 108 in the drums 1, 2, 3 and 4 and also in the screen 105. The apparatus is then taken apart and the gold recovered.

Having described my invention, I claim:

1. A gold separator including a plurality of superimposed communicating drums, a chute communicating with the uppermost drum, a sump communicating with the lowermost drum, a coarse screen extending vertically through said drums and said sump, and a plurality of fine concentric screens of different diameters secured to said coarse screen in each of said drums.

2. A gold separator including a plurality of superimposed communicating drums, a chute communicating with the uppermost drum, a sump communicating with the lowermost drum, a coarse screen extending vertically through said drums and said sump, a

plurality of fine concentric screens of different diameters secured to said coarse screen in each of said drums, said fine screens being located in alternate sides of 5 said drums successively.

3. A gold separator including a plurality of superimposed communicating drums, a chute communicating with the uppermost drum, a sump communicating with the lowermost drum, said chute, said sump and the rear half of said drums being formed in one 10 casting, the forward half of said drums being formed in another single casting, angle irons secured to the rear casting at the forward edges thereof, angle irons secured to 15 said forward casting at the rear edges thereof, and provided with vertical slots in their outstanding flanges, bolts extending through said slots and screwing into the adjacent flanges of the angle irons on said rear casting for adjusting said castings vertically 20 with relation to each other to vary the size of the ports between said drums, and means in said drums for collecting the gold.

4. A gold separator including a plurality of superimposed communicating drums, a chute communicating with the uppermost drum, a sump communicating with the lowermost drum, said chute, said sump and the rear half of said drums being formed in one 25 casting, the forward half of said drums being formed in another single casting, angle irons secured to the rear casting at the forward edges thereof, angle irons secured to 30 said forward casting at the rear edges thereof, and provided with vertical slots in their outstanding flanges, bolts extending through said slots and screwing into the adjacent flanges of the angle irons on said rear casting for adjusting said castings vertically 35 with relation to each other to vary the size of the ports between said drums, a coarse screen extending through said drums and said sump, and fine screens of different 40 diameters secured to said coarse screen concentrically in said drums. 45

In testimony whereof I affix my signature.
WILLIAM CORDICE McLAUGHLIN.
